DOOR STRUCTURE

Arthur A. Van Atta, Marion, Ohio

Application June 7, 1937, Serial No. 146,898

6 Claims. (Cl. 189—46)

This invention relates to a door structure of the hinged adjustable type, capable of being fitted as a screen or other type of door, but it is designed primarily for use as a screen door.

The object of the invention is to provide, in a manner as hereinafter set forth, a hinged adjustable door structure capable of being adjusted to compensate for different widths and heights of door openings.

A further object of the invention is to provide, in a manner as hereinafter set forth, a door structure of the class referred to including a hinge unit and an adjustable unit and with said units having coating means to provide for the adjusting of one relative to the other to compensate for door openings of different widths and for maintaining the units in adjusted relation.

A further object of the invention is to provide, in a manner as hereinafter set forth, a door structure of the class referred to including a hinge unit and a door unit and with means coacting with said units for adjusting the length of these latter to compensate for door openings of different heights.

Further objects of the invention are to provide, in a manner as hereinafter set forth, a door structure of the hinged adjustable type which is simple in its construction and arrangement, strong, durable, quickly adjusted and detachably secured in its adjusted position, readily installed with respect to a door opening, thoroughly efficient in its use and comparatively inexpensive to manufacture.

With the foregoing and other objects in view, the invention consists of the novel construction, combination and arrangement of parts as will be more specifically described and as illustrated in the accompanying drawings wherein is shown embodiments of the invention, but it is to be understood that changes, variations and modifications may be resorted to which fall within the scope of the invention as claimed.

In the drawings:

Figure 1 is a front elevation, broken away, of the door structure illustrating it in full lines in non-adjusted position and in dotted lines in adjusted position relative to width and length.

Figure 2 is a rear elevation of the door structure illustrating it in full lines in non-adjusted position and in dotted lines in adjusted relation to width and length.

Figure 3 is a fragmentary view in front elevation of the upper portion of the door structure upon an enlarged scale.

Figure 4 is an exploded fragmentary view in

front elevation of the lower portion of the door structure upon an enlarged scale,

Figure 5 is a section on line 5—5, Figure 1, upon an enlarged scale,

Figure 6 is a section on line 6—6, Figure 1 upon an enlarged scale,

Figure 7 is a section on line 7—7, Figure 3,

Figure 8 is a section on line 8—8, Figure 7,

Figure 9 is a section on line 9—9, Figure 3,

Figure 10 is a section on line 10—10 Figure 2, 10 upon an enlarged scale with the cover plate and handle grip not shown.

Figure 11 is a section on line 11—11, Figure 10,

Figure 27 is a section on line 27—27, Figure 4, and

Figure 28 is a section on line 28—28, Figure 1 upon an enlarged scale.

40

The door structure may be hinged at the left thereof and adjusted as to width at the right, or it may be hinged at the right thereof and adjusted as to width from the left. The door structure is shown by way of example as being 45 hinged at the left and adjusted as to width at the right thereof.

With reference to Figures 1 to 22, the door structure includes a body unit 27 (Figures 1 and 2) which also constitutes a carrier for the units 50 employed to adjust the structure as to width and length. The unit 27 is of rectangular contour and is formed lengthwise thereof with an opening 28 across which extends a reticulated panel or screen 29 (Figures 1, 2, 3, 9, 10 and 11). The 55

upper and lower end walls 30, 31 respectively of the opening 28 are oppositely outwardly inclined. The unit 27 is constructed of sheet metal of the desired gauge and has anchored to its outer face at the left thereof the leaves 32 of upper, intermediate and lower superposed hinges 33. The other leaves of the hinges 33, indicated at 34 extend laterally from the left side edge of the unit 27 and are adapted to be fixedly secured to a wall or other support in proximity to a door opening in such wall or support.

The unit 27 includes an inner side member 35 (Figures 1 and 2) substantially of strap-like form provided with two spaced pairs of spaced reinforcing ribs 36 lengthwise of its outer face. The side member has its inner face in proximity to its inner lengthwise edge formed lengthwise thereof with a rib 37 extending from a point in proximity to the end wall 30 of opening 28 to a point in proximity to the end wall 31 of such opening. The ribs 36 and 37 in transverse cross section are rounded and are struck from the side member 35. The unit 27 includes upper and lower oppositely disposed flat plate-like end members 38, 39 (Figures 1 and 2) substantially of right angled triangular contour. The width of member 38 is less than that of member 39. The member 38 on its outer face in proximity to its top edge is formed with a pair of spaced transversely extending ribs 40 (Figures 1 and 3) of a length less than the width of such member. The member 39 on its outer face is formed with a pair of spaced transversely extending ribs 41 (Figure 1) of less length than the width of member 39 and spaced from the top and bottom edges thereof. The member 38 on its inner face, in proximity to its lower edge is formed with a rib 42 (Figures 1 and 4) disposed at an inclination corresponding to the inclination of the said lower edge. The member 39 on its inner face in proximity to its upper edge, the latter being disposed at an inclination, is provided with a rib 43 (Figure 1) extending at an inclination corresponding to the inclination of the said upper edge. The ribs 40, 41 are horizontally disposed. The ribs 40, 41, 42 and 43 are rounded in transverse cross section and struck from said end members. The ribs 40 are disposed in parallelism; the ribs 41 are disposed in parallelism. The ribs 41 centrally thereof are cut out to form openings 44 (Figure 15) for a purpose to be referred to. The member 38 has its top formed with an inwardly extending flange 45 (Figure 12) terminating in a reinforcement 46. The member 35 (Figures 5 and 6) has its outer lengthwise edge provided with an inwardly extending flange 47 terminating at its inner end into a reinforcement 48. The members 38 and 39 abut the flange 47 and are overlapped by the reinforcement 48. Welded to the outer face of the member 35 in proximity to its outer end and extending upon and welded to the member 38 is a facing strip 49 formed on its outer face with a pair of ribs 50 of the same contour and arrangement as the ribs 40. The members 38, 39 are welded to the inner face of the member 35.

The reticulated panel 29 has one side marginal portion thereof mounted on the rib 37 and positioned on said side marginal portion is a retainer 51. The said side marginal portion, rib 37 and retainer 51 are detachably connected together by the holdfast means 52. The upper marginal portion of the panel 29 is mounted upon the rib 42. The latter is formed with barbs 53 (Figures 20, 21 and 22) which extend through the upper mar-

ginal portion of the panel 29. The barbs 53 are struck from the rib 42. Positioned on the upper marginal portion of the panel 29 is a retainer 54. The member 38 is bent upon itself at its lower edge to prevent the bottom of the member 38 having a sharp edge. The bent portion of the member 38 is indicated at 55 (Figures 3 and 12) and is arranged on the outer face of such member. Extending through the bent portion 55, retainer 54, upper marginal portion of the panel 29 and rib 42 are holdfast means 56 (Figures 2 and 3) for detachably connecting the panel 29 to member 38. The top of member 39 is bent outwardly upon itself as indicated at 57 (Figure 14) to prevent member 39 having a sharp top edge. The lower end marginal portion of panel 29 is positioned on the rib 43 and arranged on such marginal portion is a retainer 58. Extending through portion 57 of member 39, rib 43, lower end marginal portion of panel 29 and retainer 58 are holdfast means 59 (Figure 2) for detachably connecting panel 29 to member 39.

Secured to the inner faces of members 38, 39 by welding or otherwise, are the ends of a hollow support 60 of semi-circular cross-section. The other side marginal portion of the panel 29 is arranged upon the support 60 and positioned upon such marginal portion of panel 29 is a retainer 61. The said other side marginal portion of panel 29, support 60 and retainer 61 are secured together by holdfast devices 62 whereby the panel 29 is detachably connected to the support 60.

The door structure includes an adjustable unit 63 for adjusting the width of the door structure and formed of sheet metal. The unit 63 includes a body part 64 of strap-like form and of the desired length and width. The outer lengthwise edge of the body part 64 is provided with an inwardly extending flange 65 merging at its inner end into a reinforcement 66.

The body part 64 is formed integral with its inner lengthwise edge in proximity to its upper end with an inwardly extending arm 67 formed with an opening 68. Secured upon the outer face of the body part 64 and the outer face of the arm 67 (Figure 7) is a cover member 68a provided with a pair of lengthwise extending parallel ribs 69 which at their inner ends are slidably mounted on the ribs 40. The upper rib 69 has an opening 70 which aligns with the openings 68. The upper portion of the body part 64 and the inner face of arm 67 bear against the member 38. The latter is formed with an elongated slot 71 at the inner face of the arm 67. The unit 63 is adjustably mounted on the unit 27 and has its upper portion secured in adjusted position by a headed bolt 72 (Figure 7) extending through opening 68 and slot 71. The bolt 72 carries a clamping nut 73 which binds against the rear face of member 68a (Figure 8) for detachably connecting body part 64 to member 38. The body part 64 has its outer face provided lengthwise thereof with an upper pair of parallel reinforcing ribs 74 (Figure 2) and a lower pair of parallel reinforcing ribs 75 lengthwise thereof. The lower ends of the ribs 74 are spaced from the upper ends of the ribs 75. The body part 64 centrally of its inner side edge has an inward extension 76 (Figure 1). The unit 63 is formed with a horizontal slot 77 (Figure 10) which is arranged in body part 64 and extension 76. The slot 77 is arranged between the ribs 74 and 75 (Figure 1). A cover plate 78 is provided for the slot 77 and is welded to the outer face of body 75.

part 64 and arm 76. Welded or otherwise secured to the outer face of the body part 64 and disposed over the cover plate 78 is a hand grip 79.

The body part 64 in proximity to its lower end has extending inwardly from its inner lengthwise edge an arm 80 formed with an opening 81 (Figure 19). Welded or otherwise secured to the outer face of body part 64 and extension 80 is a cover plate 82 (Figure 4) provided on its outer face with hollow ribs 83, 84 which at their inner ends are slidably mounted on the ribs 41 (Figure 4). Rib 83 has an opening 85 which aligns with the opening 81. The member 39 (Figure 19) is formed with a slot 86 positioned at the inner face of the arm 80. Extending through the opening 81 and slot 86 is a headed bolt 87 carrying a clamping nut 88. The lower portion of unit 63 is adjustably mounted on the member 39 and is secured in its adjusted position by the bolt 87 and nut 88 which is to bind against the inner face of member 39. The openings 79 and 85 permit of access to the bolts 72, 87 respectively.

The side member 35 of the unit 27 (Figure 1) has welded to its outer face thereof in alignment with the inner end of hinge 33 (Figure 1) an inwardly extending plate 89 formed with ribs 90 which are mounted upon the portion of the ribs 41. The inner lengthwise edge of the side member 35 centrally thereof has an inward arm 90^a (Figure 5) which aligns with the extension 76 (Figure 2). Secured to the outer face of side member 35 and extension 90^a is a cover 91 formed with openings 92, 93.

The door structure includes a handle bar consisting of a pair of end terminal portions 94, 95 (Figures 5 and 10) and an inset intermediate portion 96 (Figures 5 and 10). The terminal portion 94 is secured against the inner face of the side member 35 by holdfast devices 97, 97 (Figure 5) which align with the openings 92, 93 respectively in the cover 91. The end terminal portion 95 (Figure 10) is of less length than the end terminal portion 94 of the handle bar and is slidably connected to the unit 63 by a headed bolt 99 extending through the slot 77 (Figure 10) and carrying a clamping nut 100. The bolt 99 extends through the support 60, panel 29 and retainer 61. The manner of connecting the handle bar to the unit 63 in a manner as shown in Figure 10 permits the adjusting of the unit 63 laterally with respect to the unit 27, when occasion requires.

The side member 35 of unit 27 corresponds in length to the body part 64 of unit 63 (Figure 9). Body part 64 is provided at its top with an inwardly extending flange 101 (Figure 13) which terminates at its inner end in a reinforcement 102. The flange 101 and reinforcement 102 overlap the flange 45 and reinforcement 46, but flange 101 and reinforcement 102 are slidable relative to flange 45 and reinforcement 46.

The door structure includes a unit 103 (Figures 1 and 4) for adjusting the length thereof and to compensate for the width of the door structure when the latter is adjustable relative to width by the unit 63. The unit 103 with reference to Figures 4, 15, 16 and 17 includes a vertical stem 104 which extends through the openings 44 (Figure 15) and is provided at its upper end with a stop 105. The stem 104 is formed lengthwise thereof with an elongated slot 106 of less length than the length of the stem. The lower end of stem 104 merges into a flat cuff 107 which is arranged against the outer face of member 39. The cuff 107 is flat, of substantially oval contour in ver-

tical section, closed at its top and bottom and open at its sides. The front of cuff 107 is formed with reinforcing ribs 108. Carried by the cuff 107 is a pair of laterally extending oppositely disposed plates 109, 110. Plate 109 is of less length than plate 110 and has an end portion 109^a thereof extending into cuff 107 and fixedly secured thereto in any suitable manner. The outer end of plate 109 (Figure 17) is inwardly flanged as at 111 (Figure 28) and overlaps and slidably engages with the inwardly extending flange 47 on the outer side edge of the side member 35 of unit 27 (Figure 15). The plate 110 is adjustable laterally with respect to the cuff 107. The adjustment of the plate 110 is had simultaneously with the adjustment of the unit 63 (Figures 1 and 13). The outer end of plate 110 (Figure 15) is formed with an inwardly extending flange 113 (Figure 27) which overlaps and slidably engages with the flange 65 of the unit 63 (Figure 1).

The cuff 107 and plates 109, 110 are arranged against the outer face of member 38 of unit 27 (Figure 2). The member 38 of unit 27 has an opening 114 (Figure 16). Extending through slot 106 and opening 114 is a headed bolt 115 provided with a clamping nut 116. Slot 106 (Figures 1 and 18) permits of the unit 103 being extended in a direction to increase the length of the door structure. The bolt 115 and nut 116 coact to detachably secure unit 103 in its adjusted or its normal position. The plates 109 and 110 are formed with reinforcing ribs 117 (Figure 18).

Referring to Figures 23, 24 and 25, a modified form of adjustable door structure in accordance with this invention is illustrated and includes a body unit 118, a unit 119 for increasing the width of the door structure and a unit 120 for increasing the length of the door structure. The unit 118 is formed of two sections 121, 122. The section 122 extends inwardly from the inner lengthwise edge of section 121. The sections 121, 122 of unit 118 are formed with stamped out portions thereof to provide superposed spaced panels 123. Unit 118 has extending laterally from its outer lengthwise edge superposed spaced hinges 124. The unit 118 has a portion 118^a thereof slidably mounted on the section 122 of unit 118. The unit 119 is formed with stamped out portions 125 which are slidably mounted on panels 123. The units 118 and 119 are provided with means for adjustably connecting them together and the said means corresponds to the means illustrated and described for connecting the units 27 and 63 together. The unit 120 is constructed in the same manner as the unit 103 referred to and is arranged relatively to the units 118, 119 in the same manner as the unit 103 is arranged to units 27 and 63. The door structure shown in Figure 23 is an all metal construction and the reticulated panel is disposed with. The section 122 of unit 118 is formed of an upper portion 126, an intermediate portion 127 and a lower portion 128. The said portions 126, 127 are welded together. The lower end of the portion 127 is arranged relatively to the portion 128 in the same manner as the upper part of the portion 127 is arranged relative to the portion 126. The section 121 of unit 118 is provided with lengthwise extending reinforcing ribs and the unit 119 is also provided with lengthwise extending reinforcing ribs. The said ribs of the said units are indicated at 129 and are set up in the same manner as the lengthwise extending ribs of the units 27 and 63.

In reference to Figure 26, a modified form of door structure is disclosed and will be of the

same construction as that illustrated with respect to the form shown by Figures 1 to 22, with this exception, that in lieu of employing the reticulated panel 29, a transparent or translucent panel 139 reinforced throughout by an embedded metallic reticulated member is employed. The panel 130 extends across and is arranged rearwardly of the opening 131 and the unit 132 which corresponds to the unit 27. The inwardly extending ribs on the unit 132 are indicated at 133. The ribs 133 correspond to the ribs 42, 43 on the members 38, 39. The panel 138 is mounted in a frame 134 and said panel is detachably secured to the ribs 133 by the holdfast device 135. Otherwise than that as stated the form of door structure shown in Figure 26 will be the same as that shown in Figures 1 and 2.

What I claim is:

1. A door structure comprising a unit adapted to have one side thereof hinged to a support, an adjustable unit for increasing the width of the door structure, said adjustable unit slidably engaging with said hinged unit, said units including coacting means for detachably securing the adjustable unit in normal and adjusted positions including mutually engaging slidable and securing ribs, an adjustable lower unit for increasing the length of the door structure, said lower unit including parts slidably engaging with said hinged and adjustable units, one of said parts being bodily movable with said adjustable unit, and said hinged and lower units having coacting means for maintaining the lower unit in normal and adjusted positions including an upstanding stem and an upwardly bent lower portion thereof for engaging parts of the sliding structures.

2. In an adjustable door structure, a body unit, a laterally adjustable unit positioned against the outer face of one side of the body unit, said units having coacting means for detachably securing the adjustable unit in normal and adjusted positions, a vertically adjustable stem adjusted independent of said units, slidably coupled against the outer face of the lower portion of the body unit and terminating at its lower end into the closed top of an upstanding cuff, a plate fixed to, extending laterally from one side of the cuff and slidably engaging with one side edge of the body unit, a slideable plate carried by and extending laterally from the other side of said cuff and provided with means for coupling it to the outer side edge of the adjustable unit to provide for such plate bodily moving with the adjustable unit, and said body unit and stem having coacting means for detachably securing the stem in normal and adjusted positions.

3. In an adjustable door structure, a body unit formed of a side member and a pair of spaced end members, an adjustable unit slidably engaging with one and adjustably secured to both of the end members, including mutually engaging slidable and securing ribs, a vertically adjustable stem interengaging with the front of the lower portion of and detachably secured to said body unit, a cuff closed at its top and bottom and open at its sides, the top of the cuff being connected to the bottom of said stem, a plate fixed at its inner end to and extending laterally from one side of the cuff and having its outer end provided with means slidably engaging with one side edge of the body unit, and a shiftable plate slidably mounted in and extending laterally from the other side of said cuff and having its outer end

provided with means slidably engaging in the outer side edge of said adjustable unit.

4. An adjustable door structure comprising a unit adapted to have its inner side hinged to a support and including an inner side member and top and bottom members secured to and extending laterally with respect to the inner side edge of said side member, an adjustable unit for increasing the width of the door structure and including an outer side member having extending from its inner lengthwise edge, upper and lower parts opposing the outer faces of and being of materially less length than said top and bottom members, the upper end of said top member and the upper end of said outer side member having inwardly extending coacting means for slidably connecting the outer side member to and for suspending it from said top member, said upper part and top member having coacting means to provide a pair of spaced parallel horizontal guides for said outer side member, said lower part and bottom member having coacting means to provide a pair of spaced parallel horizontal guides for said outer side member, means coacting with a guide of each pair of guides for slidably connecting said outer side member to and for securing in its adjusted position with respect to the hinged unit, a reticulated panel having upper, lower, and inner side marginal portions connected with said inner side and top and bottom members, and means independent of the outer side member for connecting the outer side marginal portion of said panel with said top and bottom members.

5. In a door structure of that type having a vertical element of strap-like form for adjusting the width thereof, the said structure including a hinged rectangular body unit constituting a carrier adapted for horizontally slidably suspending on one side of the front thereof the said element, said body unit formed of an inner side member substantially of strap-like form having its outer lengthwise edge formed throughout with an inwardly extending flange, top and bottom members of plate-like form disposed in spaced relation, having their inner side portions secured to the inner face of and extending laterally from the inner lengthwise edge of said side member, said top and bottom members being of a width to have their outer side portions extend under said element, the top edge of the said top member being formed with an inwardly extending flange for slidably connecting said element thereto and for suspending the latter, said top and bottom members formed with offset horizontal superposed guides for said element, means coacting with said top and bottom members and with certain of said guides for releasably and adjustably securing said element to said top and bottom members, and a reticulated member having its top and bottom portions secured respectively to said top and bottom members, its inner side portion to said side member and being of a width to have its outer side extended under said element, said top and bottom members being substantially of right angled triangular contour and oppositely disposed, said top member being so arranged to provide its inclined edge at its bottom, said bottom member being so arranged to provide its inclined edge at its top.

6. In an adjustable door structure, an upstanding inner side member of strap-like form, a top member secured to and extending laterally from the inner lengthwise edge of said side member, said top member having its top formed with an

inwardly extending flange, a bottom member secured to and extending laterally from the inner lengthwise edge of said side member, a horizontally adjustable outer side member of strap-like form positioned against the outer faces of said top and bottom members at the outer side portions of the latter, said outer side member being formed at its top with a rearwardly extending flange overlapping, enclosing and slidably connected to the flange of said top member for suspension from the latter, said outer side member being formed with upper and lower inwardly extending horizontal parts of less length than and for overlapping the outer faces of said top and bottom members, each of said parts being apertured, said top and bottom members formed with slots aligning with the apertures in said parts, said top and bottom members and said parts having coacting portions to provide superposed spaced

horizontally disposed guides for said outer side member, said inner and outer side members having their outer lengthwise edges formed throughout with inwardly extending flanges, said top and bottom members being substantially of right angled triangular contour and oppositely disposed, a rectangular reticulated panel having the top, bottom, inner side and outer side parts thereof opposing the inner faces of said top, bottom, inner side and outer side members, the said parts of said panel having portions offset with respect to the remaining portions thereof, means for securing said offset portions of said top, bottom and inner side parts of said panel to said top, bottom and inner side members, and means for securing the offset portion of the outer side part of said panel with said top and bottom members. 5 10 15

ARTHUR A. VAN ATTA.
